UNITED STATES PATENT OFFICE.

FRANK LIBBY, OF LOS ANGELES, CALIFORNIA.

METHOD OF MAKING PLATES FOR MULTICOLOR PRINTING.

Application filed October 30, 1926. Serial No. 145,186.

This invention relates to methods of making multi-color prints, and an important object of the invention is to materially lower the cost of color reproduction.

According to one of the present-day methods in multi-color reproduction, separate half-tones or etchings are made of the picture that is to be reproduced, and the engraver works upon each plate by removing portions of its surface, thus producing a different plate for each of the colors in which the reproduction is to be rendered. Thus, if there are to be three colors in the finished print, the engraver prepares three plates. The engraver receives relatively high wages and the preparation of the plates by him in this manner, consumes considerable time, thus making the old method very expensive.

By another method, at present employed, the operations are purely mechanical and color screens are employed. This latter method is also very expensive.

By this new method, the expense of producing each color plate is no greater than is the expense of making an etching from an ordinary line drawing. In fact, the operation for making the individual plates is the same, the invention lying in the difference of treatment of the drawings from which the plates are made.

By this new method the color separation is provided for by the artist, who prepares a series of hand-made drawings, one drawing for each color.

The accompanying drawings illustrate the results of certain of the operations performed by the artist.

Figures 1, 2 and 3 are facsimiles of the artist's drawings for effecting color-separation.

The new method is performed as follows:

A drawing is made by the artist and this drawing may be the original drawing. This drawing is made either in an eradicable medium as, for example, pencil, or in a color having no material actinic effect upon a photographic plate exposed thereto. In either event, the drawing thus made may be used for one of the finished color-separation drawings. For example, this drawing may be, what I shall term the blue drawing, illustrated in Figure 1, since it may be the one from which the color plate for printing in blue may be made. The artist applies ink lines to this pencil drawing, only

on those portions which are to be reproduced in blue. The ink lines of this drawing are made at an approximately definite angle or angles. For example, for the lighter shades, the artist has employed horizontal lines 4, and these lines may be placed at different intervals and may be made of varying thicknesses in order to produce the desired shadings. Still heavier shades are secured by ink lines 5 crossing the lines 4 substantially at right-angles, and, in this instance, the lines 5 are substantially vertical. The lines 4, 5 will be drawn only upon those areas that are to be reproduced in blue or in a tint in which blue is present.

Where a shade of maximum depth is desired, the ink will be applied solidly, as indicated at 6.

It will thus be seen that I am able to produce any shade of blue that I may wish for any part of the picture, from the most delicate shade to the solid blue color.

After the blue drawing is completed, the artist places over it a tracing medium, such, for example, as tracing paper, tracing cloth or celluloid, on which the artist makes a second color-separation drawing. Assuming, for example, that this second drawing is to be used in making the plate for printing red, it may be termed the red drawing. The artist proceeds to draw in ink lines over those portions that are to be reproduced in red or in a tint in which red is present. Where a red color is desired in the printed reproduction, the ink lines will be drawn upon areas of the tracing medium that do not overlie the ink line areas of the blue drawing, but where a tint produced by blending red and blue is desired, the ink lines will be drawn upon some portion of the area of the tracing medium lying over the ink line area of the blue drawing.

For example, referring to Figure 2, the ink lines 7 are placed at a different angle than the ink lines in Figure 1. These lines, for example, may be approximately 30 degrees to the horizontal and, as in the blue-separation drawing, these lines may be of varying thicknesses and may be placed at varying intervals in order to secure the desired shades of color. Still deeper shades may be produced by crossing the lines 7 at substantially right-angles with other lines 8 which, accordingly, are approximately at an angle of 60 degrees to the horizontal.

Some part of this drawing may have the

ink applied solidly, as indicated at 9, in order to secure a maximum depth of the color in the finished reproduction.

If the printed reproduction is to be rendered in three colors, ink lines on the red drawing may also be drawn on those portions of the tracing medium that are to be reproduced in a tint in which red and the third color are present.

Where the printed reproduction is to appear in only two colors, no further drawings need be prepared but, in this instance, it is assumed for example, that it is desired to have the finished reproduction appear in three colors. Accordingly, the artist will remove the completed red drawing from over the blue drawing and replace it with a tracing medium, of the character mentioned above, and the artist will apply ink lines 10, as indicated in Figure 3, to those parts of the drawing that are to appear in the finished reproduction in a third color or in a tint in which blue or/and red are present with the third color. For example, it may be assumed that this third drawing is to be used for making the plate for printing the color yellow. I will, accordingly, term it the yellow drawing. The lines 10 are placed at a different angle to the horizontal than the lines 4, 5, 6 and 7. The lines 10 may be, for example, approximately 60 degrees from the horizontal and the thickness of said lines will be varied, and they will be placed at varying intervals to obtain the desired shades. Deeper shades will be secured by the artist applying ink lines 11, crossing the lines 10 at approximately an angle of 90 degrees. This drawing, also, has the ink applied solidly, as indicated at 12, to secure the deepest shade of yellow.

Where a yellow color is desired in the printed reproduction, the ink lines will be drawn upon areas of the third tracing medium that do not correspond to the ink line areas of the blue and red drawings. Where a tint, produced by blending of blue and yellow, is desired, the ink lines will be drawn upon some portion of the area of the third tracing medium corresponding to the ink line area of the blue drawing. Where a tint, produced by blending of red and yellow, is desired, the ink lines will be drawn upon some portion of the area of the third tracing medium corresponding to the ink line area of the red drawing. Also, when a tint, produced by blending of blue, red and yellow, is desired, the ink lines will be drawn upon some portion of the area of the third tracing medium corresponding to the ink line areas of the blue and red drawings.

If it were desired to make the reproduction in four colors, the procedure would be the same as above described, excepting that the angle between the lines on the different drawings would be approximately $22\frac{1}{2}$ de-

grees instead of 30 degrees, and a fourth drawing would be made after the manner in which the third drawing was made excepting for the areas covered by the lines and the angle of said lines.

In order to facilitate drawing the lines in each drawing at approximately the angle selected for that particular drawing, I may, before proceeding with the drawing of the ink lines, draw upon the tracing medium several guide lines, indicated in the drawing by dotted lines 13. These lines are drawn with a suitable protractor or draftsman's angle so that they will extend accurately at the angle selected.

It is to be understood, however, that the lines drawn by hand by the artist need only approximate the angle of the guide lines 13. In fact, slight variations from said angle will produce the desired artistic effect, as results from free-hand work distinguishing from mechanically produced lines.

If the first drawing has been made with pencil or other eradicable medium, the pencil or other eradicable marks will be erased or otherwise eradicated.

The next operation in this new method is to make, from the different drawings thus completed, photo-etchings or photo-mechanical printing plates, as they are sometimes termed, in a manner well understood in the art relating thereto. There will thus be produced a plate for printing blue, a plate for printing red and a plate for printing yellow and these plates will be printed in that order. Thus, not only will the printed reproduction have in it the three primary colors, blue, red and yellow, but it may also have in it any desired number of tints that would result from mixing the primary colors in various proportions, since the artist, in effect, obtains the tints by varying the spacing, thickness and arrangement of the ink lines in the drawings, said lines being accurately reproduced in color by the etched

plates.

Preferably, the photo-etchings of the drawings will be made on a single plate so that they will appear on the plate upon exactly the same scale, and the plate will then be cut to separate the photo-etchings for printing. In this way perfect registration is facilitated.

From the foregoing it will readily be seen that there is no expensive alteration of plates as required by one of the old processes, and that the color reproduction has the artistic qualities of free-hand drawing which cannot be said for the old processes that employ color screens.

That this new method is far more economical than any of the old multi-color processes, can be appreciated from the fact that the drawings made by the artist in this method are all simple line-drawings

and the etchings are produced from said drawings at from one-third to one-fifth of the cost of the multi-color plates produced by the old methods now in use. For example, by photo-engraving the three plates of a three-color picture, as a single plate and separating them afterwards, the zinc plates can be produced for a small picture for approximately \$4.00; whereas, by the old methods now in use, multi-color plates for the same sized picture, would cost from \$20.00 to \$50.00, depending upon whether the plates are made with the so-termed process plates or are made with Benday and color-separation.

By my new method, color reproduction can be made with as great a variety of tones and colors as by any method now in use, and, at the same time, the color reproduction by my method has a new, unusual, characteristic and attractive appearance.

Because of the free-hand drawing done by the artist without the use of any mechanical means or screens, there is a freedom about the appearance of the reproductions produced by my method that gives them an artistic appearance.

A great advantage of my method is that it makes possible the use of multi-color printing in a large number of instances where, by the older methods now in vogue, the cost would be prohibitive.

Because of the artist being guided by the drawing showing through the tracing medium, the drawings for the different colors can be made in but little more time than is necessary for completing the original drawing.

As an aid in making the drawings for the different colors, the artist may first outline in pencil the different areas over which he intends applying ink lines. It is to be understood that the ink lines are applied with pen, and that where the ink is applied solidly, it may be done by the pen or a suitable brush.

I claim:

1. The method of making plates for multi-color printing consisting in making a plurality of free-hand drawings with ink lines, corresponding areas of the drawings having the lines positioned at a materially different angle when the drawings are superposed, and making photo-etchings of said drawings.

2. The method of making plates for multi-color printing consisting in making a

plurality of free-hand drawings with ink lines of varying thickness, corresponding areas of the drawings having the lines positioned at a materially different angle when the drawings are superposed, and making photo-etchings of said drawings.

3. The method of making plates for multi-color printing consisting in making a plurality of free-hand drawings with ink lines varying in spacing, corresponding areas of the drawings having the lines positioned at a materially different angle when the drawings are superposed, and making photo-etchings of said drawings.

4. The method of making plates for multi-color printing consisting in making a free-hand drawing with an eradicable medium of the subject that is to be reproduced, drawing ink lines upon that area of the drawing that is to be reproduced in one of the primary colors or in a tint in which said primary color is present, placing a tracing medium over said drawing, drawing ink lines upon some portion of the area of the tracing medium lying over the first-mentioned area and at a materially different angle to the first-mentioned lines, eradicating the eradicable medium from the first-mentioned drawing, and making photo-etchings of the respective drawings.

5. The method of making plates for multi-color printing consisting in making a free-hand drawing in a color having no material actinic effect upon a photographic plate exposed thereto, drawing ink lines upon that area of the drawing that is to be reproduced in one of the primary colors or in a tint in which said primary color is present, placing a tracing medium over said drawing, drawing ink lines upon some portion of the area of the tracing medium lying over the first-mentioned area and at a materially different angle to the first-mentioned lines, and making photo-etchings of the respective drawings.

6. The method of making plates for multi-color printing consisting in making a plurality of free-hand drawings with ink lines, corresponding areas of the drawings having the lines positioned at a materially different angle when the drawings are superposed, making photo-etchings of said drawings on a single plate, and cutting the plate to separate the photo-etchings.

Signed at Los Angeles, Cal., this 19 day of October, 1926.
